UNITED STATES PATENT OFFICE.

THOMAS SODEN, OF NEW YORK, N. Y.

SOFA-BEDSTEAD.

SPECIFICATION forming part of Letters Patent No. 256,925, dated April 25, 1882.

Application filed March 16, 1882. (No model.)

To all whom it may concern:

Be it known that I, THOMAS SODEN, a citizen of the United States, residing at New York city, in the county of New York and State of New York, have invented certain new and useful Improvements in Sofa-Bedsteads, of which the following is a specification, reference being had therein to the accompanying drawings.

This invention has relation to sofa-bedsteads; and its object is to provide a simple, durable, and comfortable lounge or sofa which may in a moment be converted into an equally comfortable bed; and the novelty consists in the construction of the same, as will be hereinafter more fully set forth, and more particularly pointed out in the claim.

In the accompanying drawings similar letters of reference indicate like parts of the invention.

Figure 1 is a front perspective view of my improved lounge, with the ornamental back rail elevated to show that it is detachable. Fig. 2 is a transverse sectional elevation; and Fig. 3 is a similar view, showing the sofa in position for use as a bed.

A is the rectangular base-frame, provided with the ordinary legs, a. A similar frame, B, is hinged to the base-frame A, and is the seat of the lounge when folded, while the reverse or bottom side is provided with a suitable

spring-mattress, C, which forms one-half of the bed-surface when opened. This frame B is provided with the upright head-rests D D, to the rear of which are attached the feet d, which rest on the floor and support the frame-section B when in use as a bed.

E is the back of the lounge, and is provided with an ornamental rail, e, which is removed when in use as a bed. This back E is hinged to the base-frame section A by the hinged braces F. This allows the back E to be folded down, as shown in Fig. 3, and the spring-mattress G, secured to the back E, to form one-half of the bed. The mattress-back G during the day is always exposed to the air, and consequently is kept thoroughly ventilated.

Having thus described my invention, what I claim as new and useful, and desire to secure by Letters Patent of the United States, is—

In a convertible sofa-bedstead, the frame A, provided with the hinged back E and brace F, in combination with the reversible front portion, B C D, substantially as and for the purpose set forth.

In testimony whereof I affix my signature in presence of two witnesses.

THOS. SODEN.
